AROMATICS PRODUCTION

Henry D. Noll, Philadelphia, Pa., assignor to Air Products and Chemicals, Inc., Philadelphia, Pa., a corporation of Delaware

Filed Oct. 14, 1965, Ser. No. 495,932

10 Claims. (Cl. 260—672)

The present invention relates to the production of industrially valuable aromatic and/or alkylaromatic hydrocarbons in desirably high yield from a hydrocarbon charge stock, particularly from petroleum distillates.

Among the objects of the invention are to produce from a hydrocarbon distillate increased yields of xylenes and benzene, the latter being optionally converted to cyclohexane.

These objects are accomplished, in accordance with the invention by reforming a naphtha charge stock of any origin and of suitable boiling range, and removing from the reformate light paraffins and naphthenes boiling below benzene, the remaining heavier portion of the reformate is split to provide (1) a C₆—C₈ fraction and (2) a C₉₊ fraction. Each of these fractions is separately treated under selected conditions to produce high yields of benzene from the first fraction and to obtain high yields of xylenes from the second fraction. Thus, the first fraction is extracted with a selective solvent to obtain an aromatic concentrate containing benzene and C₇—C₈ alkyl benzenes. This aromatic extract is fractionated to separate an overhead fraction rich in benzene, a middle cut rich in toluene and a bottoms fraction containing the C₈ aromatic hydrocarbons, chiefly xylene. The middle cut (toluene) is subjected to demethylation in the presence of suitable catalyst and the C₆+ liquid effluent recycled to the main aromatic fractionator. In this manner the products removed from the main fractionator consist of a benzene fraction and a C₈ aromatics fraction consisting chiefly of xylenes.

The C₉₊ fraction separated from the initial reformate is separately demethylated under conditions selected to obtain high yields of C₈ aromatics which are recovered from the remaining products in the dealkylation effluent, unconverted and heavier (C₉₊) hydrocarbons being continuously recycled to the dealkylation reactor.

The operation of the invention will be understood and the beneficial advantages appreciated from the detailed description which follows read in connection with the accompanying drawing illustrating by simplified schematic flow diagram a preferred embodiment thereof. Conventional auxiliary equipment, such as heat exchangers, compressors, reboilers, pressure reduction valves, circulating pumps, etc. have largely been omitted from the drawings for clarity in presentation.

There is shown in the flow diagram at 10 a hydrogenative refining system wherein the naphtha charge is contacted with hydrogen and passed over catalyst under conditions designed to reduce any sulfur and/or nitrogen compounds present. Of course, if the selected charge stock is relatively free of sulfur and nitrogenous contaminants the hydrorefining treatment need not be practiced. However, if the hydrocarbon charge contains as much as 0.02% sulfur compounds it is desirable that these be removed, since the presence of sulfur compounds in the feed to the subsequent reforming operation reduces the yield of aromatics obtained and also reduces catalyst life.

The refined product from 10 is sent to a gas separator at 11 where the H₂S and H₂ together with light hydrocarbon gases are removed overhead by line 12 and the remaining liquid hydrocarbons passed to the reforming system through line 13. The hydrogen-containing gas from 11 may be recycled to the refining step at 10, if desired after treatment by scrubbing in known manners to remove H₂S and/or ammonia compounds therein, or a portion of the

2

gas may be discharged and the remainder recycled to the treating reactor at 10, without purification, making up with the fresh hydrogen supplied an equilibrium hydrogen-rich stream of the required degree of purity.

5 The reforming section 14 is similar to that generally employed in hydrogenative reforming of naphtha over platinum catalyst, comprising generally three or more reactors in series. In typical reforming of hydrocarbons over platinum catalyst a number of simultaneous reactions generally take place, including: dehydrogenation of naphthenes, dehydrocyclization of paraffins, hydrocracking of paraffins, and isomerization of paraffins and part of the naphthenes. By proper selection of catalyst and operating conditions, the comparative rates of these various reactions can be controlled to some extent. In the present instance the catalyst and operating conditions are selected to favor increased aromatics production.

The effluent from the reforming operation at 14 is flashed at 15 to remove hydrogen and lower gaseous hydrocarbons, withdrawn by line 16, part of which hydrogen-rich gas is recycled to the reforming reaction. The remainder of the gas is used in the pretreating section 10 and elsewhere in the system in which hydrogen is required.

The liquid product from 15 is sent by line 17 to a stabilizer 18 and splitter 19 to effect removal of any remaining hydrogen and light hydrocarbons such as those boiling below benzene. C₆ paraffins and lighter products are thus separated in the overhead streams 20 and 21 from the higher boiling liquid hydrocarbons withdrawn through line 22. The products in line 22 will thus include principally benzene and higher boiling cyclic and acyclic hydrocarbons. Splitter 19 may be operated at about atmospheric pressure and at a cut point of about 75—78° C. to obtain substantially all of the benzene and higher boiling hydrocarbons in the bottom product.

The products in line 22 are fractionated at 23 at a suitable cut point to separate an overhead fraction composed chiefly or almost entirely of C₆—C₈ hydrocarbons, and a bottoms fraction composed of C₉ and heavier hydrocarbons. The cut point for this fractionation may be taken within the C₉ paraffin boiling range or at about 140—150° C. so that substantially all of the trimethyl benzene compounds remain in the bottoms fraction while substantially all or most of the C₈ aromatics are discharged in the overhead vapors withdrawn in line 24.

The overhead fraction in line 24 is subjected at 25 to separation of aromatics from the accompanying hydrocarbons in any known manner. In the preferred operation such separation is accomplished by extraction with a selective solvent for the aromatic components such as: N-methyl pyrrolidone, N-hydroxyethyl pyrrolidone, butyrolactone, triethyleneglycol, dimethyl formamide. These solvents are diluted with a small amount of water or other anti-solvent in known manner to improve selectivity. The obtained aromatic concentrate, after being freed of extraction solvent, is sent by line 26 to the main aromatics fractionator 27.

The C₉₊ hydrocarbons withdrawn from fractionator 23 through line 28 are subjected to hydrogenative dealkylation at 29, conditions being selected to favor production of xylene compounds. Any non-aromatic compounds present are cracked to acyclic hydrocarbons boiling below benzene. The effluent reaction products from dealkylation at 29 are stripped of hydrogen and low boiling hydrocarbons (through C₅) in stabilizer 30 and remaining liquid products sent by line 31 to fractionator 32 wherein separation is made between C₈ and lighter products taken overhead through line 33 and C₉₊ hydrocarbons recycled to dealkylation in reaction system 29 by means of line 34.

The charge to the main aromatics fractionator 27, thus comprises aromatics concentrate essentially free of

acyclic compounds (C_6-C_8) from the aromatic extraction systems 25 and the product from line 33 which is rich in C_8 aromatics but which also contains accompanying benzene and toluene formed by dealkylation in 29. The fractionator 27 is operated to separate the charge into an overhead fraction consisting almost entirely of benzene of high purity (nitration grade), a heart cut consisting largely of toluene and a bottoms cut composed of C_8 aromatics. The benzene fraction is withdrawn through line 35 and can be sent to storage as a product of marketable purity. If desired, however, all or part of the benzene can be hydrogenated to more valuable cyclohexane as indicated at 36. The C_8 aromatics cut is withdrawn through line 37 and sent to storage 38. The stored product comprises a mixture of the xylene isomers with some ethyl benzene.

The toluene cut is withdrawn at an intermediate level of fractionator 27 through line 39 and subjected to demethylation as indicated at 40. The reaction product from demethylation is stripped of hydrogen and hydrocarbons boiling below benzene in stabilizer 41 while the higher boiling liquid hydrocarbons (C_6 and C_7), composed of product benzene and unreacted toluene are returned to the main aromatics fractionator 27 through line 42. In the main fractionator these returned products will be separated into benzene and toluene, the former being collected with the benzene in line 35 while the latter is again sent to demethylation in 40 to form additional benzene.

It will thus be seen that in the particular arrangement provided there is obtained from a suitable boiling range naphtha, aromatic products having high industrial demand and enhanced market value consisting of a xylene fraction which can be marketed as such or split into its several isomers, and a benzene fraction which in itself is in demand and which optionally can be readily converted in high yields to presently more valuable cyclohexane. The toluene cut, which is less profitable, is continuously recycled to extinction with production of additional benzene. By separately demethylating the C_9+ fraction and the C_7 fraction, conditions in each reaction are more readily controlled to obtain maximum yields of xylene and benzene respectively with only small amounts of the C_8 charge being dealkylated beyond the dimethyl benzene stage, and even this small amount being readily recovered as benzene or by conversion to benzene. By provision of the single main fractionator for all of the aromatics products, moreover, considerable saving in equipment and operation costs are had.

The operating conditions for each of the reactions will now be described.

Desulfurization of charge

As explained above, this step need be practiced only if the naphtha employed contains more than 0.02% S and/or more than 100 p.p.m. N. The pretreatment is carried out in a manner and under conditions generally employed in connection with pretreatment of a naphtha charge to be subjected to hydrogenative reforming over supported platinum catalyst. In the typical catalytic hydro-treatment for removal of sulfur and nitrogen compounds, the naphtha charge is passed over cobalt molybdate catalyst at 650-750° F. and at pressure of about 400-750 p.s.i.g. at hourly liquid volume space rate of 1 to 4 and at a hydrogen to oil ratio of 1 to 3. For charge stocks containing nitrogen as well as sulfur contaminants pressure at the higher level of the indicated range is preferred and space rates in the lower part of the stated range. A typical commercial catalyst that can be employed for this purpose is described in U.S. Patent No. 2,755,257. By the described hydrogenative treatment, the sulfur and nitrogen contaminants in the charge stock are converted largely to H_2S and NH_3 respectively which, together with hydrogen and light hydrocarbons (through C_4 or C_5) are stripped out at 11 from the remaining liquid products sent to reforming. If desired, hydrogen-rich gas is recycled to the hydrotreating

reaction, a portion being removed and replaced by hydrogen from line 16 to maintain desired hydrogen concentration and purity.

REFORMING SECTION

Hydrogenative reforming over platinum-alumina catalyst is well known for upgrading of gasoline as well as for production of aromatics. A number of platinum-alumina reforming catalysts are available commercially containing from about 0.1-1.0% platinum (generally about 0.5% Pt.) on an adsorptive alumina carrier which is more usually of the gamma or eta type; in some instances the catalyst is used in sulfided state. These catalysts differ in acidity as a result of difference in content of halogen or other properties of the alumina carrier. While most of the available commercial platinum-alumina catalysts can be employed for the presently described reforming step, to obtain selectively high yields of desired aromatic compounds without excessive hydrocracking and isomerization, it is preferred to employ platinum catalysts of low acidity value. Such catalysts are generally free from fluoride and contain halogen, if any, only in the form of chloride in an amount less than the platinum content of the catalyst. A recommended catalyst for this purpose is that described in U.S. Patent No. 3,189,559. In reforming operations over platinum catalyst a wide range of operating conditions have heretofore been suggested including pressures of 100 to 1000 pounds per square inch, temperatures of 750 to 1050° F. and space rates of 0.1 to 5.0 with hydrogen to oil ratios of 1/1 to 10/1 or more. To favor aromatics production, in addition to using the low acidity platinum alumina catalyst heretofore described, it is advantageous to observe operating conditions within a more narrow range. The temperature should be at about 930° F. ± 20 ° F when starting on fresh active catalyst and should be increased progressively to about 1000° F. as the catalyst becomes less active over the period of onstream use until regeneration is effected to restore the catalyst activity. Space rates of about 1 to 3 volumes of oil per hour per volume of catalyst, preferably at about 2, and pressures of about 300 to 500 p.s.i.g. favor aromatics production particularly when using low acidity platinum-alumina catalyst. Hydrogen-rich gas should be recycled at a rate to provide H_2 /oil ratios of about 5 or more, preferably about 6 moles/mole of hydrocarbon feed. Under these conditions continuous operation of several months or more and at times up to about a year is made possible before it is needed to regenerate the catalyst to restore activity.

In the reforming operation, hydrogen is produced as a result of cyclization and dehydrogenation of hydrocarbons. A portion of the produced hydrogen is recycled in the desired quantity to the reforming operation, while the excess hydrogen is sent to the hydro-pretreating step and elsewhere in the system as required.

AROMATICS EXTRACTION

The C_6-C_8 fraction of the reformat (line 24) will contain over 50%-70% or more aromatics boiling in the range from benzene to o-xylene (about 80-145° C.) in addition to acyclic compounds, chiefly paraffins, in the C_6-C_8 boiling range. In the preferred embodiment separation of the aromatics is achieved by extracting the hydrocarbon charge in multistage counterflow apparatus with about 3 to 4 volumes of N-methyl pyrrolidone containing 15% water and 10-15% pentane. The solvent is separated from the aromatic hydrocarbons by distillation and reused for further extraction.

DEMETHYLATION OF TOLUENE

While the demethylation of toluene can be accomplished thermally, in such operation temperatures above about 1225° F. are required with accompanying excessive degradation of product. It is therefore preferred to employ catalytic demethylation over highly active chrome-alumina catalyst containing 15-25% Cr_2O_3 supported on an alu-

mina base obtained by dehydration of an alumina hydrate containing at least 50% beta alumina trihydrate. Conditions used for this operation are described in U.S. Patent No. 3,178,486. In general, the demethylation should be carried out at about 1000-1200° F., pressures of 650-800 pounds per square inch, and rates giving contact time of 50-150 seconds. The preferred operation in accordance with one specific embodiment is carried out at a pressure of 700 pounds per square inch, maintaining a temperature of 1150° F. (at the reactor outlet) at a hydrogen/oil mole ratio of 5 (7:1 total recycle gas to oil) and at a space rate of about 0.45, resulting in contact time of about 70 seconds. The catalyst employed is that described in Example I of the aforesaid U.S. Patent No. 3,178,486, having an activity corresponding to a k_T value (at 873° K.) of approximately 0.602 as compared to $k_T=0.144$ for the non-catalytic thermal dealkylation at this temperature.

DEALKYLATION OF C_9 AROMATICS

The hydrocarbon charge subjected to dealkylation in system 29 will contain typically

	Percent
C_9 and C_{10} paraffins	3-6
C_9 aromatics	60-70
C_{10} aromatics	20-30
C_{11} aromatics	Circa 2
Indene and naphthalene, less than	0.5

By subjecting this charge to dealkylation conditions over chrome-alumina catalyst, the small amount of C_9 and C_{10} paraffins in the charge will be all cracked out chiefly to low molecular weight (C_5 and lower) gases. The alkyl aromatics will largely demethylate stepwise obtaining largely xylene isomers in the liquid product with some formation of benzene and toluene.

Conditions of reaction favoring production of xylene with minimized further demethylation to toluene and benzene are the use of equal or somewhat higher pressures and lower temperatures and shorter contact time than those employed in the demethylation of toluene. For xylene production from C_9 aromatics, temperatures should be in the order of 1100 to 1150° F., pressures of 750 to 900 p.s.i.g. and contact times generally below 1 minute, which entail space rate (LHSV) approaching or somewhat exceeding 1 (vol./hr./vol.). In a preferred specific embodiment dealkylation of the C_9 aromatics fraction is effected at about 1130° F. (reactor outlet temperature), pressure of 800 p.s.i.g., at 7:1 moles recycled gas to oil (corresponding to about 5/1 H_2 :oil mole ratio) and at a liquid hourly space velocity of 1.2 (vol./hr./vol.), affording a contact time of about 40 seconds.

Example

The 85-200° C. virgin naphtha fraction derived from a Kuwait crude, analyzed as follows:

	Percent by wt.
Paraffins	62.0
Naphthenes	24.0
Aromatics	14.0
Sulfur total about	0.03

The above-described naphtha fraction is desulfurized in a hydro-pretreater over cobalt-molybdate catalyst, resulting in a product having less than 50 p.p.m. sulfur, and essentially free of nitrogen. The desulfurization is effected at 700-750° F., 400 p.s.i.g., at a liquid hourly space rate of 4 (vol./hr./vol.) and a recycle gas mole ratio of 2.5.

The products from the hydro-pretreater are stripped of hydrogen, H_2S , and light gases and the remaining C_5+ liquid sent to hydrogenative reforming over platinum-alumina catalyst in a three-reactor fixed bed system with intermediate reheaters. The reforming is effected at an average temperature of 935° F., 380 p.s.i.g. at the inlet to the first reactor, at an hourly volume space rate of 2 and at a gas recycle ratio 8 moles gas per mole of liquid

hydrocarbon feed. The resulting reformat product has the following composition:

	Wt. percent
H_1 and C_1 to C_4 paraffins	22.6
C_5 paraffins	10.0
C_6 paraffins	8.7
C_6 and C_7 naphthenes	0.6
Benzene	2.4
C_7 paraffins	6.9
Toluene	9.8
C_8 paraffins	2.7
C_8 aromatics	13.9
C_9 aromatics	13.9
C_{10} aromatics	5.5
Olefins	1.3
Other hydrocarbons	1.7

The reformat is cooled and flashed at the existing pressure to remove hydrogen rich gas for recycle to the reforming section and for other uses. The degassed product is further treated to separate out products boiling below benzene and the remaining liquid product (C_6 aromatics to 200° C.) is fractionated to provide a C_6 to C_8 hydrocarbon fraction sent to aromatics extraction and a C_9+ hydrocarbon fraction sent to dealkylation. Of the original 8.7% paraffins in the reformat, 76% thereof is removed in the stabilizer overhead, the remainder appearing in the benzene and heavier liquid fraction sent to aromatics extraction.

The composition of the C_6 to C_8 fraction is as follows, the aromatics being substantially recovered in full by the extraction.

	Feed to Extraction Weight Percent	Extract Weight Percent
Benzene	6.2	9.8
Toluene	25.2	39.8
C_8 aromatics	33.5	50.4
Non-aromatics	35.1	

The C_6 - C_8 extract separated from the aromatics extraction zone 25 flows to the main aromatics fractionator 27, where it is separated into a benzene stream 35, a toluene stream 39, and a xylene stream 38.

The C_9+ hydrocarbon fraction separated in fractionator 23 is sent to the dealkylation zone 29. The fresh feed-stock, exclusive of recycle supplied through line 34 will consist of:

	Percent
C_8 aromatics	4
C_9 aromatics	64
C_{10} aromatics	25
C_{11} aromatics	2
Paraffins and other hydrocarbons	5

Said feedstock is directed over a catalyst consisting of 20% Cr_2O_3 on 80% eta alumina at a pressure of 800 p.s.i.g and a contact time of about 46 seconds at about 5 to 1 hydrogen to oil ratio (7 to 1 gas to oil recycle ratio) at an average reaction temperature of about 1130° F. (1040° F. inlet, 1135° F. outlet) at a liquid hourly space velocity of about 1.05 volumes of oil per hour per volume of catalyst. Particular attention is directed to the feature of utilizing the combination of low reaction temperature and short contact time, whereby the dealkylation of the C_9 hydrocarbons favors formation of xylene with a smaller amount of toluene and a still smaller amount of benzene.

The reaction conditions employed result in about 70-80% conversion of the C_9+ hydrocarbons charged to conversion; 50-70% by volume of the liquid product is composed of C_8 aromatics. The remaining 20-30% of unconverted and partially converted product is recycled to dealkylation.

The dealkylated product flows through line 33 for admixture with the aromatics from the extraction zone 25, and the mixture flows to the fractionator 27.

The C₇ aromatics stream in line 39 is demethylated over the chrome-alumina catalyst above described in a system comprising two reactors in series at an inlet temperature of 1090° F. to the first reactor and at 1130° F. to the second reactor, at a pressure of 700 p.s.i.g., at a total hourly space rate of 0.4 (vol./hr./vol.) and at a 5:1 mole H₂/oil ratio. These conditions obtain a residence time of about 70 seconds in the two reactors and result in about 70% conversion of the toluene charged. Unconverted toluene is recycled to extinction.

Obviously, many modifications and variations of the invention as hereinbefore set forth may be made without departing from the spirit and scope thereof, and therefore only such limitations should be imposed as are indicated in the appended claims.

What is claimed is:

1. In the method of producing benzene and xylenes from a hydrocarbon reformate rich in aromatics the improvement which comprises: removing hydrocarbons boiling below about 75-78° C. from said reformate; fractionating the remaining hydrocarbons after such separation into (a) a light fraction composed predominantly of C₆ to C₈ hydrocarbons, and (b) a heavy fraction consisting essentially of C₉ and higher hydrocarbons; extracting aromatic hydrocarbons from said light fraction (a); subjecting said heavy fraction (b) to selected conditions of mild hydrogenative dealkylation at temperatures between about 1100 and about 1150° F. over active chrome-alumina catalyst favoring production of xylenes; separating C₆ to C₈ hydrocarbons from said mild dealkylation while continuously recycling to said dealkylation products boiling above xylenes; combining the separated C₆ to C₈ hydrocarbons stream with said aromatic extract stream from the light fraction and subjecting the combined streams to fractional distillation to provide: (c) an overhead cut consisting substantially of benzene; (d) a bottoms cut composed essentially of C₈ aromatic hydrocarbons predominating in xylenes; and (e) a middle cut consisting essentially of toluene; subjecting said middle cut (e) to severe demethylation over active chrome-alumina catalyst at temperatures between about 1000 and about 1200° F. under selected conditions favoring production of benzene; removing products boiling below benzene from the effluent from said severe demethylation reaction, while returning the produced benzene and unreacted toluene to fractional distillation with the aforesaid combined streams so as to obtain (1) additional recovered benzene products and (2) toluene for recycling to demethylation; and controlling the mild dealkylation of the C₉ plus hydrocarbons fraction to provide shorter residence time than that employed in the severe demethylation of the toluene.

2. In the method in which a hydrocarbon fraction is converted to mononuclear aromatic hydrocarbons by steps comprising hydrogenative reforming of a naphtha fraction, extractive distillation of at least a portion of the reformate, and hydrogenative catalytic dealkylation of at least a fraction of the alkylated aromatics, the improvement which consists of: subjecting a mixture of hydrogen and feedstock to high pressure catalytic hydrodesulfurization; hydrogenatively reforming the hydrodesulfurized feedstock over a platinum on alumina catalyst; separating and withdrawing from the reformate the liquid boiling below about 75° C. and the liquid boiling above about 200° C. to provide a C₆ to C₁₁ fraction boiling in the 80 to 200° C. range; splitting the C₆ to C₁₁ fraction to provide a C₆ to C₈ fraction and a C₉ to C₁₁ fraction, said splitting being at a cut point in the range from 140 to 150° C.; extracting the C₆ to C₈ fraction to provide a nonaromatic raffinate by product and a C₆ to C₈ aromatic fraction; exhaustively converting the C₉ to C₁₁ fraction to C₆ to C₈ aromatic hydrocarbons by exhaustive recycling through a mild hydrodealkylation zone containing chromia on alumina catalyst, the contact time being less than about 60 seconds, there being several mols

- of hydrogen per mol of normally liquid hydrocarbons, and the temperature being in the range from about 1100° F. to about 1150° F., whereby any nonaromatic components are converted either to C₆ to C₈ aromatic hydrocarbons or to by products comprising nonaromatic hydrocarbons boiling significantly below benzene; admixing the C₆ to C₈ aromatic fractions from the extraction with the C₆ to C₈ aromatic hydrocarbons from the mild dealkylation steps and fractionally distilling to provide a benzene fraction, a xylene fraction, and a toluene fraction; exhaustively recycling the toluene through a severe demethylation zone for total conversion to benzene, the recycle passing through said fractional distillation of C₆ to C₈ aromatic fractions, the hydrodealkylation zone containing chromia on alumina catalyst, the contact time being in the range from about 50 seconds to about 150 seconds and longer than the contact time in the mild dealkylation reaction, there being several mols of hydrogen per mol of normally liquid hydrocarbon, and the temperature being higher than in the mild dealkylation reaction but less than about 1200° F.; and transferring hydrogen generated in the reforming zone for consumption in each of the zones for hydrodesulfurization, mild hydrodealkylation, and severe hydrodemethylation.
- 25 3. A method in accordance with claim 2 in which the feedstock to the hydrogenative reforming zone has an end boiling point providing a reformate containing only trace amounts of C₁₁+ hydrocarbons, whereby substantially only C₆ to C₁₀ hydrocarbons are converted selectively to xylenes and benzene.
- 40 4. A method in accordance with claim 2 in which hydrogen generated in the reforming zone is employed in converting at least a portion of the benzene to cyclohexane.
- 35 5. A method in accordance with claim 1 in which the extraction of aromatic hydrocarbons from the light fraction composed predominantly of C₆ to C₈ hydrocarbons is conducted using a solvent consisting of about 15% water, about 15% pentane and about 70% by weight methyl pyrrolidone, there being from about 3 to about 4 volumes of solvent per volume of C₆ to C₈ hydrocarbon.
- 45 6. A method in accordance with claim 1 in which the mild dealkylation of C₉ plus hydrocarbons is conducted at about 800 p.s.i.g. pressure at about 1130° F. for a contact time of about 40 seconds.
- 50 7. A method in accordance with claim 1 in which the severe demethylation of the toluene fraction is conducted at a temperature of about 1150° F. at a pressure of about 700 p.s.i.g. for a contact time of about 70 seconds.
- 55 8. A method in accordance with claim 1 in which the fractional distillation of the C₆ to C₈ aromatics is conducted to permit benzene, xylene, and other materials to contaminate the toluene fraction, but to achieve a benzene fraction particularly free from toluene and a xylene fraction particularly free from toluene.
- 60 9. A method in accordance with claim 1 in which the mild dealkylation and severe demethylation reactions are conducted in the presence of a recycle gas to normally liquid hydrocarbons of about 7 to 1, and the hydrogen purity is sufficient to maintain a hydrogen to normally liquid hydrocarbon ratio of at least about 5 to 1.
- 65 10. A method in accordance with claim 1 wherein product benzene is hydrogenated to obtain cyclohexane.
